UNITED STATES PATENT OFFICE.

CHARLES H. MERRITT, OF DANBURY, CONNECTICUT, ASSIGNOR TO JOHN T. WARING, OF NEW YORK, N. Y.

HATTER'S TANK.

SPECIFICATION forming part of Letters Patent No. 314,461, dated March 24, 1885.

Application filed December 20, 1883. (No model.)

To all whom it may concern:

Be it known that I, CHARLES H. MERRITT, of Danbury, in the county of Fairfield and State of Connecticut, have invented a new and useful Improvement in Hatters' Tanks, of which the following is a specification.

This invention relates to tanks for hot water, which are used in hat manufacture for dipping the hat-bodies while performing the various operations of sizing, scalding, shrinking, &c. When designed for a number of operators, such a tank is commonly provided with a shelf or plank around its edge, and is termed a "battery." The steam arising from such tanks is very annoying to the workmen, and hinders them in their work by rendering it difficult for them to see, and is also injurious to health; and the object of my invention is to enable the steam to be more completely got rid of and carried off than has been possible with the hoods resembling inverted funnels commonly arranged over the tanks.

The invention consists in the combination, with a battery-tank and a surrounding plank, of a cover or steam-chamber above the tank, a guard or curtain practically closing the entrance to the cover or chamber, and a draft or outlet pipe arranged to carry off the steam or vapor from the cover or chamber.

The invention also consists in the combination, with a tank used for dipping hat-bodies, of a cover or steam-chamber above the tank having an opening closed by a yielding curtain, and a draft or outlet pipe arranged to carry off the steam or vapor from said cover or chamber.

The invention also consists in the combination, with a battery-tank used for dipping hat-bodies and a surrounding plank, of a cover or steam-chamber above the tank, having an opening closed by a yielding curtain, and a draft or outlet pipe arranged to carry off the steam or vapor from said cover or chamber.

In the accompanying drawings, Figure 1 is a plan of a battery-tank having my invention applied to it. Fig. 2 is a vertical section of said tank on the line $x-x$, Fig. 1, showing the entrance to the steam-chamber as practically closed by guards, and Fig. 3 is a section similar to Fig. 2, showing the openings into the chamber closed by guards consisting of yielding curtains.

Similar letters of reference designate corresponding parts in all the figures.

A designates the battery-tank, which is surrounded by the plank B, and which in itself is like the tanks heretofore used. Water is maintained therein up to a proper level, and steam to heat the water is admitted by a pipe, a , under control of a valve, a' , to a coil, a'' , in the bottom of the tank.

Above the tank is placed a steam-chamber or cover, C, from which extends a draft or outlet pipe, D, and the entrance to the chamber is practically closed by guards. This chamber may be polygonal, and the lower portions, C', of its sides may be inclined inward slightly, as shown in Fig. 2.

The tank A being circular and the chamber polygonal, there will be formed on each of the sides of the chamber, and opposite each of the sides of the polygonal plank B, an opening, b , sufficient in size to enable the hat-bodies to be inserted into the tank, and not large enough to allow the steam to escape into the room when the draft or outlet pipe is used.

The inclined sides C' of the chamber C form guards, which practically close the entrance to the tank in that they, in connection with the draft-pipe, effectually prevent steam from escaping into the room.

The steam-chamber C in Fig. 3 is shown as polygonal, and its guards instead of being rigid consist of yielding curtains. These curtains may be of any kind of flexible fabric or material, as shown at C'; or they may be of rigid material, such as a piece of board, as shown at C''. In the latter case the curtain should be attached by hinges c , so that it may swing inward. In either case the curtain is capable of yielding to permit of the hat-bodies being introduced into the tank.

By the use of the draft-pipe a suction is produced from the room into the steam-chamber, and hence the steam arising from the hat-bodies after they are withdrawn from the tank and while upon the plank will a large part of it be drawn into the steam-chamber, especially with the form of guards shown in Fig. 2.

What I claim as my invention, and desire to secure by Letters Patent, is—

1. The combination, with a battery-tank and a surrounding plank, of a cover or steam-chamber above the tank, a guard or curtain

practically closing the entrance to said cover or chamber, and a draft or outlet pipe arranged to carry off the steam or vapor from said cover or chamber, substantially as and for the purpose described.

2. The combination, with a tank used for dipping hat-bodies, of a steam-chamber above the tank having an opening closed by a yielding curtain, and a draft or outlet pipe arranged to carry off the steam or vapor from said cover or chamber, substantially as described.

3. The combination, with a battery-tank used for dipping hat-bodies and a surrounding plank, of a cover or steam-chamber above the tank having an opening closed by a yielding curtain, and a draft or outlet pipe arranged to carry off the steam or vapor from said cover or chamber, substantially as described. ¹⁵
